UNITED STATES PATENT OFFICE

149,942

DESIGN FOR A DRINK DISPENSER CABINET

Richard E. Harvuot, Inglewood, Calif., assignor
to Interstate Aircraft and Engineering Corp.,
El Segundo, Calif., a corporation of California

Application July 29, 1946, Serial No. 132,087

Term of patent 3½ years

(Cl. D52—3)

To all whom it may concern:

Be it known that I, Richard E. Harvuot, a citizen of the United States and resident of the city of Inglewood, county of Los Angeles, State of California, have invented a new, original, and ornamental Design for a Drink Dispenser Cabinet, of which the following is a specification, reference being had to the accompanying drawings, forming a part thereof, in which:

Fig. 1 is a plan view of a drink dispenser cabinet, showing my new design;

Fig. 2 is a side elevational view;

Fig. 3 is a front elevational view;

Fig. 4 is a rear elevational view; and

Fig. 5 is a view in perspective.

I claim:
The ornamental design for a drink dispenser cabinet, substantially as shown.

RICHARD E. HARVUOT.
